United States Patent Office.

STEPHEN CHAMBERLIN, OF BOSTON, MASSACHUSETTS.

Letters Patent No. 74,891, dated February 25, 1868.

IMPROVED TIP-SLED.

The Schedule referred to in these Letters Patent and making part of the same.

TO ALL WHOM IT MAY CONCERN:

Be it known that I, STEPHEN CHAMBERLIN, of Boston, in the county of Suffolk, and State of Massachusetts, have invented an Improved Tip-Sled; and I do hereby declare that the following, taken in connection with the drawings which accompany and form part of this specification, is a description of my invention sufficient to enable those skilled in the art to practise it.

The object of my invention is to construct sleds for cartage of coal, sand, gravel, &c., that their contents may be slid or tipped out from them, the same as with common dump or tip-carts; and my invention consists in so mounting a sled-body upon its runners that its rear end may be tipped down to a sufficient angle to discharge the load by gravity.

The drawings represent a sled embodying my invention.

A shows a side elevation; B, an end elevation thereof. *a a* denote the runners; *b*, the sled body, mounted on an axle, *c*, which is supported in high bearings, *d*, as seen at A. The axle turns or tips in these bearings, *e*, holding each axle down, and allows the body to be tipped, as seen by the lines in red at A. The front end of the body is supported on an upright, *f*, and is held down thereto by a ring and hook, as seen at *g*, or by any other suitable device, the ring being slipped from the hook to tip the sled, as will be readily understood. The rear end of each runner from the vertical plane of the axle is made short, and is cut away to allow the body, when tipped, to come down to, or almost to, the surface of the ground, as seen at A, the load being thereby dumped without danger of overturning, or of tipping up the runners.

The means of connecting the body to the runners or runner-frame or truck, and the general construction and arrangement, may be varied from that described, although the construction shown is considered the simplest and most practical. Double runners may be used if or when desirable.

The invention supplies a great want in moving coal, gravel, &c., when snow lies upon the ground, and obviates the necessity of using wheel-carts for tipping, or of shovelling out the material if sleds are used.

It will be obvious that the bearings *a* may be placed across the sled, instead of lengthwise thereof, so as to have the body tip at the side instead of at the back, as will be readily understood.

I claim, in combination with the sled-runners, a body so mounted as to tip, substantially as described.

Witnesses:

FRANCIS GOULD,
J. B. CROSBY.

STEPHEN CHAMBERLIN.
